UNITED STATES PATENT OFFICE.

JULIUS WODISKA, OF NEW YORK, N. Y.

CHAIN SHOT.

1,165,053.

Specification of Letters Patent. Patented Dec. 21, 1915.

Application filed January 5, 1915. Serial No. 559.

To all whom it may concern:

Be it known that I, JULIUS WODISKA, a citizen of the United States, residing in the city, county, and State of New York, have 5 invented a certain new and useful Improvement in Chain Shot, of which the following is a specification.

My invention relates to chain shot for that class of guns known as ordnance and 10 for such guns whether for naval or land use and, if the latter, whether for use as a field gun or for use in permanent emplacements.

More particularly my invention relates to 15 chain shot for a gun of the class specified in which the gun is provided with two barrels or bores having axes which diverge slightly so that the projectiles, when they leave the gun, continue to diverge from one another 20 and stretch the connecting chain thus forming, in effect, a continuous projectile of considerable length transverse to the direction of fire. Projectiles of this class, while long known, may now find a new field of application as destroying means for aeroplanes, 25 dirigible balloons and the like.

My invention provides an improved chain shot the leading character of which is the 30 uniting of the shot by chain of considerable length passing through openings in the points of said shot, said chain being held, up to the time the projectiles are fired, within the body of one or both projectiles and capable of being extended as the projectiles 35 increase their distance from the gun; at all stages during flight, therefore, this extensible chain tends to be kept tightly stretched between the projectiles proper.

So far as I am aware, in the prior art, 40 chain shot have always been connected together by chains of definite and rather limited length so that the area swept over by the chain has been correspondingly limited.

My improved chain shot is provided with 45 means which prevent any entanglement of the chain in the bore of the gun as well as any wedging or wearing action of the chain upon the same.

The object of my invention is to provide 50 a chain shot for a gun of the type specified which shall be free of many of the disadvantages hitherto appurtenant to guns of this class and which, without increase of

powder charge or size of gun, shall be capable of greater destructiveness.

My invention will be better understood by referring to the accompanying drawings in which—

Figure 1 represents a side elevation of a field gun for use with my improved chain shot; Fig. 2 is a plan view of Fig. 1 taken from above; Fig. 3 is a front view of Fig. 1; Fig. 4 is a longitudinal section taken through the axes of the two barrels of the gun; Fig. 5 is a view showing the behavior 65 of my improved chain shot after it has left the gun of the previous figures; Fig. 6 shows my invention as applied to a chain shot for a three barrel gun; Fig. 7 is an enlarged longitudinal section through one of the projectiles proper of my improved chain shot and Fig. 8 is a view, similar to Fig. 7, showing a modified form of such single projectile.

In the drawings the gun 1 is mounted upon a carriage 2 of usual type. The gun has two barrels 3, 4 opening and diverging from a common explosion chamber 5. The breech of the explosion chamber is closed by a breech block 6 hinged at 7 and locked into place by any usual locking device 8. 75 The gun is preferably, but not necessarily, made from one piece. At the explosion chamber the gun is cylindrical externally and provided with peripheral ribs 9, 10 which are beveled on their rear faces; a short tubular cradle 11, having its top wall removed and provided with trunnions 12 journaled in opposite forks of the carriage and provided with peripheral rings 13, 14 which abut against the beveled faces of ribs 9, 10 respectively embrace and support the gun. In constructing and assembling the gun rib 13 should be made in two pieces and fastened to the remaining portion of the cradle after first being positioned against 85 rib 9.

A transverse worm 15, operated by hand wheel 16 and mounted in upwardly projecting portions of the cradle 11, engages a peripherally disposed worm gear 17 (Fig. 4) 100 fixed to the gun. One of the trunnions 12 carries a segmental gear 13' which is engaged with a worm 18 attached to the side of the carriage and operated by a hand wheel 19.

By the use of hand wheel 16 the gun may

be rotated about its mean axis so as to deliver its projectiles either in a vertical plane or a horizontal plane, or in any plane intermediate thereto.

5 By use of the hand wheel 19 the gun may be elevated or depressed (dotted lines Fig. 1 show one position in elevation).

Azimuth adjustment may be obtained by swinging the carriage as a whole upon its 10 wheels.

The projectiles 20 may be made of any usual material and preferably in two parts, viz., a body 21 and a base 22 adapted to be secured to said body.

15 In the form of projectile shown in Fig. 7 a transverse shaft, the ends of which are depressed below the surface of the body, has keyed or otherwise fastened to it a spool 24 upon which is coiled a suitable length of 20 chain or wire cable 25. The end of this shaft may be made square so as to be engaged by a suitable winding crank or handle by means of which the coiling of the chain may be accomplished.

25 Into the point of the projectile is screwed or otherwise held a guide tube 26 the outer end of which is flared as at 27. The length of this tube is preferably such that when the projectile is in the gun ready for firing its outer 30 end will extend not quite to the muzzle of the gun. The chain or cable 25 passes from the reel out of the tube.

The modification shown in Fig. 8 differs 35 from that of Fig. 7 only in that the chain or cable is coiled within the body of the projectile instead of being wound upon a spool as in Fig. 7; the end of the chain is permanently fastened to a plug 28.

The gun may be rifled and hence partially 40 choked. In loading, the two projectiles are first entered through the open breech and positioned in their respective barrels at the forward end of the explosion chamber (Fig. 4). The ends of chain 26 from each projectile may then be readily reached and connected together as at 29 externally of the 45 gun.

The explosion chamber having been given 50 its powder charge, preferably contained in a copper or other suitable shell of usual type, the breech may then be closed and the gun fired in the usual way. Or the gun may be smooth bored without choke; in such case the projectiles may be brought to the gun 55 connected in pairs and loaded into the gun at the muzzle. As the projectiles leave the gun they have a divergent direction as to one another and continue to separate. This separation will be permitted up to the length 60 of the chain connecting them, after which the projectiles will proceed parallel to one

another carrying the stretched chain between them and sweeping away everything in its path.

While for purpose of convenience I 65 have shown and described a gun of two barrels and suitable projectiles therefor, such embodiment is not essential to the practice of my invention, as the principles thereof may be applied to projectiles adapted to guns 70 of any reasonable number of barrels. In Fig. 6 I have shown in elevation a chain shot comprising three projectiles as they would appear from the front when in full flight.

As the projectiles leave the gun their axes 75 are respectively parallel to the several barrels. Immediately they have left the gun, however, the bases of the projectiles will begin to swing outwardly until the projectile axes lie transversely to the line of flight as 80 shown dotted in Fig. 5, and in Fig. 6.

Having described my invention I claim:

1. Chain shot comprising a pair of hollow projectiles having openings through their points, a chain connecting said projectiles, 85 said chain passing through said openings, and means for preventing the ends of the chain from being withdrawn from the projectiles.

2. Chain shot comprising a pair of hollow projectiles having axial openings through their tips, a chain passing through each opening, means for retaining an end of the chain within the projectile and means for connecting and disconnecting the outer ends 95 of the two chains, the major part of both chains being adapted to be contained within the projectiles up to the moment of firing but to be drawn therefrom in response to any force which tends to separate the projectiles. 100

3. Chain shot comprising a pair of hollow projectiles, a guide tube in the axis of each projectile opening into the hollow thereof, and a chain permanently connecting the two 105 projectiles, said chain passing down each guide tube.

4. Chain shot for multi-barreled guns comprising a pair of hollow projectiles having openings through their tips, a chain permanently connecting the two projectiles and passing through each opening and means for holding the chain out of contact with the gun barrels as the gun is fired. 110

In testimony whereof, I have hereunto set 115 my hand in the presence of two subscribing witnesses.

JULIUS WODISKA.
